(57) **CLAIM**

The ornamental design for triple outlet electrical socket, as shown and described.

DESCRIPTION

FIG. 1 is a perspective view of first embodiment of a triple outlet electrical socket showing my new design.

FIG. 2 is another perspective view of the triple outlet electrical socket of FIG. 1.

FIG. 3 is a left-side view of the triple outlet electrical socket of FIG. 1.

FIG. 4 is a right-side view of the triple outlet electrical socket of FIG. 1.

FIG. 5 is a front view of the triple outlet electrical socket of FIG. 1.

FIG. 6 is a bottom view of the triple outlet electrical socket of FIG. 1.

FIG. 7 is a top view of the triple outlet electrical socket of FIG. 1.

FIG. 8 is a perspective view of a second embodiment of a triple outlet electrical socket showing my new design.

FIG. 9 is another perspective view of the triple outlet electrical socket of FIG. 8.

FIG. 10 is a left-side view of the triple outlet electrical socket of FIG. 8.

FIG. 11 is a right-side view of the triple outlet electrical socket of FIG. 8.

FIG. 12 is a front view of the triple outlet electrical socket of FIG. 8.

FIG. 13 is a bottom view of the triple outlet electrical socket of FIG. 8; and,

FIG. 14 is a top view of the triple outlet electrical socket of FIG. 8.

In the figures items shown in dashed lines do not form part of the claimed design.
